UNITED STATES PATENT OFFICE.

WILLARD C. KRESS, OF BUFFALO, NEW YORK.

METHOD OF AND APPARATUS FOR REDUCING ENGINE VIBRATION.

Application filed June 18, 1920. Serial No. 389,912.

To all whom it may concern:

Be it known that I, WILLARD C. KRESS, a citizen of the United States, residing at Buffalo, in the county of Erie and State of New York, have invented new and useful Improvements in Methods of and Apparatus for Reducing Engine Vibration, of which the following is a specification.

This invention relates to multi-cylinder engines and more particularly to internal combustion engines of the single acting type such as are employed in automobiles.

The object of the invention is the provision of a novel method of and apparatus for reducing vibration of the engine and increasing its efficiency.

In its preferred embodiment, the improvements consist essentially in making the usual crank case air or fluid-tight and creating and maintaining a fluid pressure therein, to provide a sustaining medium under the pistons, and in order that ascending pistons of the engine may be returned largely by descending pistons through the intervening body of compressed fluid, thus greatly relieving the crank-shaft from the reciprocating load and diminishing vibration.

The accompanying drawing represents a vertical longitudinal section of a multi-cylinder engine embodying my improvements.

10 indicates the upper section of the crank case, and 11 the lower section bolted thereto. A suitable packing 11^a is interposed between these sections to render the crank case practically air tight.

Journalized in bearings 12 in the upper section of the crank case is the engine crank shaft 13 and bolted to the upper side 40 of said section is the cylinder block 14 in which the pistons 15 reciprocate, the latter being connected to the crank shaft by the usual connecting rods 16, so that some of the pistons ascend while others descend. Suitable packing 17 is interposed between the cylinder block and the upper crank case section 10 to insure a pressure tight joint between these parts.

In order to form a pressure tight joint at the rear end of the crank case where the crank shaft 13 projects therethrough, packing rings 18 are provided on said shaft which are fitted in the bore of a collar 19

suitably secured to the rear wall of the crank case.

The several engine-cylinders open at their lower ends into the crank case, in a manner common to this type of engine.

The means for producing and maintaining a fluid pressure in the crank-case, are preferably constructed as follows:—

Bolted or otherwise secured to the front end of the crank case so as to form a pressure-tight joint therewith, is an air or pressure pump 20, in the base 21 of which is journaled an auxiliary crank shaft 22 preferably driven from the main crank shaft 13 of the engine. As shown in the drawing, the front end of the engine crank shaft is provided with a reduced extension 23 which projects through the front wall of the crank case and to which the adjacent bored end 24 of the auxiliary crank shaft 22 is connected by a key 25 or other suitable means. To establish a pressure-tight joint at the front end of the crank case where the engine crank shaft projects therethrough packing rings 26 are mounted on the rear end 24 of the auxiliary crank shaft 22 which are fitted in the bore of a collar 27 suitably secured to the adjacent wall of the engine crank case.

28 represents the cylinder of the pressure pump in which the piston 29 reciprocates, the latter being connected to the crank shaft 22 by a connecting rod 30. Arranged in the cylinder head 31 is a port 32 communicating with the atmosphere and controlled by an inlet valve 33 which opens inwardly by the suction produced on the downward stroke of the piston of said cylinder. This valve is yieldingly held to its seat by a spring 34 surrounding the stem 35 of the valve and bearing at its lower end against the top of the cylinder head and at its upper end against a washer 36 adjustably held on the stem by a nut 37. 38 indicates the outlet port of the pump controlled by a valve 39, which opens outwardly by the pressure produced in the cylinder on the upward stroke of the piston, and which is yieldingly held to its seat by a spring 40 surrounding the stem 41 of said valve which is preferably guided in a plug 42 screwed into the upper side of the cylinder head. The air expelled through the outlet port 38 enters

a chamber 43 in the cylinder head which communicates with the interior of the crank case by a passage 44. To prevent the pressure in the crank case from increasing beyond a certain predetermined point, say 150 pounds to the square inch, a relief valve 45 is provided which is preferably arranged in the chamber 43 and adapted to open outwardly to permit any excess pressure to escape through its port 46 into the atmosphere. This valve is yieldingly held to its seat by a spring 47 surrounding the stem 48 of the valve and adjustably mounted thereon by a nut 49.

15 The operation of the engine is as follows: Assuming the engine to be running, the pump-shaft 22 is compelled to turn with the engine crank shaft 13, reciprocating the pump-piston 29. On the downward stroke 20 of this piston, air under atmospheric pressure enters the pump cylinder through the port 32, and on its upward stroke said piston expels the air from the cylinder through the outlet port 38 into the chamber 43 and thence through the passage 44 into the engine crank-case. Thus, a pressure is built up in said case which acts as a power-transmitting fluid or cushion between the adjacent ends of the several pistons, whereby 25 a portion of the explosion-pressure exerted on a descending piston is simultaneously exerted through the cushion on an ascending piston to effect its return stroke, with the result that the strain or reciprocating load 30 incident to raising or returning the pistons is largely removed from the crank shaft and the connecting rods, thus reducing vibration to the minimum. This cushioning or pressure medium acts with equal pressure on 35 the bottoms of the ascending and descending pistons, which are all of equal areas, and the pressure is thus neutralized and does not retard the movement of the pistons. It is evident that such pressure maintains a constant upward torque or pull on the crank shaft, connecting rods and pistons, but without resisting rotation of said crank shaft or movement of the pistons. The explosive force or pressure acting on a descending piston 40 does not turn the crank shaft solely through the customary direct thrust of the piston and connecting rod, but a considerable portion of that force is exerted indirectly on the crank shaft through the moving or displaced air cushion which acts on the ascending piston or pistons and causes them to pull upward on the cranks of the shaft. While the explosion stroke is thus 45 transmitted to the crank shaft partly through the ascending piston or pistons, it is evident that the shaft is relieved from a considerable part of the reciprocating load, because, after descending, a piston is not returned solely by the connecting rod and crank pin but is in a great measure re-

turned by the descending piston and the moving air cushion. It follows that vibration of the engine is greatly reduced and the efficiency of the engine increased, inasmuch as higher speeds are attainable. 70

In reciprocating engines of ordinary construction, the rapid change in piston movement falls entirely on the crank pins and connecting rods, resulting in destructive wear and vibration. By providing a sustaining 75 and transmitting medium of compressed air or similar fluid under and between the pistons, such reciprocating load or the strain of the return stroke of the piston is taken off the crank shaft, as above explained, reducing vibration and securing the above-mentioned advantages. 80

Any required pressure may be maintained in the crank case by adjusting the nut 49 to increase or decrease the tension of the spring 85 47.

The degree of air pressure necessary to neutralize the inertia loads at the forward end of the piston stroke is dependent upon the effective area of the piston and the 90 weight of the reciprocating mass, and to secure maximum efficiency, it is desirable to vary the pressure according to the speeds, since it is apparent that greater pressure is required at high speeds than at low speeds. 95 The most efficient pressure for any given speed can readily be determined in practice, and is merely a matter of adjusting the regulating nut 49. For example, an engine having a cylinder with a three-inch bore and a three-inch stroke, with a reciprocating mass weighing two pounds and a crank rotating at a speed of 4,000 R. P. M., will require a fluid pressure in the crank case of approximately one hundred and forty 100 pounds to the square inch. 105

It will be observed that the fluid-tight crank case forms a fluid-pressure chamber or conduit with which the adjacent open ends of the several engine cylinders communicate and by which they are connected, so that the pressure fluid acts as a power-transmitting medium between the descending and ascending pistons whose lower ends are exposed thereto. 110

The engine cylinders as well as the crank case are fluid-tight at all times, and a practically constant and uniform air pressure or tension is therefore maintained in the crank case and against the lower ends of the pistons throughout their forward and backward strokes. 115

I claim as my invention:

1. The herein described method of relieving the crank shaft of a single acting multiple-cylinder internal combustion engine from the reciprocating load to reduce vibration, which consists in transmitting the movement of a descending piston of the engine to an ascending one through an inter- 120 125 130

posed medium of compressed fluid, confined under pressure. 10

2. The combination of a single acting multicylinder internal combustion engine, 15
5 a fluid pressure conduit communicating with and connecting the engine cylinders, said conduit and said cylinder being fluid-tight to prevent the release of fluid and maintain a substantially constant pressure therein, the

front ends of the oppositely-moving pistons being exposed to the pressure-medium in said conduit, whereby the movement of a descending piston is transmitted to an ascending piston by said pressure-medium, and means for producing fluid pressure in 15 said conduit.

WILLARD C. KRESS.
